UNITED STATES PATENT OFFICE.

WILLIAM S. BAUGH, OF FARMERS' INSTITUTE, INDIANA.

WINDMILL.

SPECIFICATION forming part of Letters Patent No. 251,688, dated January 3, 1882.

Application filed August 30, 1881. (No model.)

To all whom it may concern:

Be it known that I, WILLIAM S. BAUGH, a citizen of the United States, residing at Farmers' Institute, in the county of Tippecanoe and State of Indiana, have invented certain new and useful Improvements in Windmills; and I do hereby declare the following to be a full, clear, and exact description of the invention, such as will enable others skilled in the art to 10 which it appertains to make and use the same, reference being had to the accompanying drawings, and to the letters or figures of reference marked theron, which form a part of this specification.

15 This invention relates to improvements in windmills, and its object is to improve the construction of the parts in such manner as that the wind-wheel will be automatically or self controlled in its action, and can be at any 20 time so operated upon by hand that its action will cease; and it consists in an improved construction of the parts of the device whereby these objects are attained, and also such other construction by which some of the actuating 25 parts are truly adjusted to their proper position, as will be fully hereinafter described in the drawings.

Figure 1 is a side elevation of a windmill having my improvements embodied therein, it 30 showing the frame-work, a shaft with vanes or rudders attached thereto, mechanism for changing the position of the vanes of the wind-wheel, and mechanism for operating a pump. Fig. 2 is also a side elevation, showing the frame- 35 work, a portion of the wind-wheel, a crank and connecting-rod for operating the pump, and the method of connecting the crank to the pump-rod. Fig. 3 is a similar view of the parts, enlarged, the frame-work being omitted. Fig. 40 4 is a side elevation of the vane or rudder shown in Fig. 1. Fig. 5 is a horizontal section, showing the frame-work and an adjustable bearing in which the shaft which supports the wind-wheel turns; and Fig. 6 is a sectional elevation, showing the same parts.

45 A represents the supporting-mast or pedestal, upon which the operating parts all rest or are attached, and it consists of four inclined ports, *a a a a*, tied or bound together in any 50 secure manner to be firm and unyielding, their top ends being secured by a cast or other metal

cap, *A'*, so formed that bolts *a'* will hold the posts *a* all firmly together and to the cap, and said cap has a central perpendicular round opening through it, so that the connection with 55 the pump-plunger may reciprocate in said central opening.

B is the wind-wheel, in disk form, having a series of inclined radial wind-slats, *b*, fixed to the concentric rings *b' b'*, which are firmly secured to radiating arms *b''*, that are fast in hub *B'*.

C is a horizontal shaft, freely revolving in bearing *C'*, formed in a projecting horizontal swinging arm, *D*, that projects from an upright 65 revolving metal hub, *D'*, having an upright or perpendicular aperture centrally through it, and bearing upon cap *A'*, as seen in Fig. 3.

C'' is a crank-disk on shaft, *C* having a crank or wrist pin, *c*, projecting horizontally 70 therefrom, to which is attached a pitman, *C'''*, pivoted to a reciprocating rod, *d'*, which freely reciprocates in guideway *d''* in an upright brace, *D''*, which may be a part of or attached to the hub *D'*; and the lower guide, *d'''*, of the 75 rod *d'* is in the top of a tube, through which it passes in its downward course to be attached to the plunger-rod of a pump or other device.

E is a horizontal rock-shaft, supported by 80 and rotating in a proper bearing in a projection, *E'*, on hub *D'*, and swinging horizontally with said hub.

F is the main vane or rudder, and in Figs. 1, 2, and 4 is seen in a horizontal position under the rock-shaft *E*, and is firmly secured to 85 said shaft by the clamps or clips *fff*. G is a smaller vane or rudder, fixed to shaft *E* by the clamp or clip *g*, and stands perpendicular, or at right angles to vane *F*. These vanes or rudders are constructed with slats and cross-ties, as seen in Fig. 1, and whenever the shaft 90 *E* rotates or vibrates the vanes or rudders move with it.

H is an arm fixed to and projecting downward from the shaft *E*, it being secured to said 95 shaft by the eye *I* and holding-screw *i* at the end opposite the vanes, as seen in Fig. 1, but free to rotate or vibrate as the shaft *E* rotates or rocks back and forth.

- *H'* is a weight adjusted on arm *H* at any desired place by holding-screw *h*.

J is an arm fixed by means of hub *J'* and

holding screw i' to shaft E, and has attached to its outer end a cord, j' , which extends upward and over a pulley, j'' , in the upright D''; thence through a slot, j''' , in hollow rod d' , down through the rod, to and within reach of an operator on the platform or ground.

K is a hollow upright pipe or cylinder, fixed at its lower end in an adjustable box, L, having a center bore to fit the exterior diameter 10 of said pipe, the flange k at the lower end thereof fitting against the under side of box L, as seen in Fig. 6, while the flange k' at the upper end fits and bears upon the upper part of the revolving hub D'. This pipe or cylinder K receives the pipe-rod d' and cord j' within it, and in which they freely work, and it also forms the axle around which the hub D' revolves, and is held in upright position by the eye a'' in cap A' and the box L. To adjust 15 the pipe K and keep it perpendicular or in relation to other working parts, the box L is adjustable in four directions between the posts a , that form the mast or pedestal A, by means of the temper-screws $l l l l$, that are fixed 20 in the four projections $l' l' l' l'$ of box L, and extend outward and through bearing-plates $l'' l'' l''$ and screw-nuts $m m m m$, so that the box is forced to move as the screw may be turned, one loosened and the other opposite 25 tightened up toward the loosened one, and hence the adjustment can be effected truly and easily, and no friction or binding of the parts will result.

N is a reciprocating rod, attached at its lower 30 end to a pump-plunger, or other thing to be operated, by or through any known and proper means, while its upper end is swiveled to the hollow reciprocating pipe-rod d' at n in such manner that the rod may be revolved, and the 35 swivel-joint n will not affect it or in any way prevent it from freely reciprocating while it turns in the pipe K.

In an easy breeze the wind-wheel B will revolve with its shaft and crank-wheel, and thereby 40 reciprocate the rod that is connected to the pump-plunger, or to any other thing to be acted upon, and all the parts will be relatively in the 45 position seen in Fig. 1; but let a strong wind strike the side of the wind-wheel, the wheel will be put into violent or quick revolution, and at the same time the wind will strike the 50

upright vane or rudder G and turn it over with the shaft E, and in doing so raises the larger vane or rudder F into the wind, and also raises the counter-weight H'; and this strong 55 wind, raising the large vane or rudder, causes the shaft E to swing around horizontally, and, if the wind is strong enough, the wheel B will be turned so as to present its edge to the wind, when its motion will be either entirely stopped 60 or it will slowly revolve. When the wind abates the counter-weight H' will gradually fall down, and as it falls the large vane or rudder F will also fall, and the wind-wheel will again come into the wind and again revolve. 65

When it is desired to stop the revolution of the wind-wheel the attendant will take hold of the cord j' at its lower end, and by a steady pull will turn the shaft E and bring the large 70 and vanes or rudders will swing around with the wind and cause the wind-wheel to turn its edge to the wind, which will stop its revolution. The cord can then be made fast and hold the parts in that position, and, as the wind 75 changes its direction, the wheel will also change its position, so as to always present its edge to the wind until the cord is released, when the parts, freed from compulsion, will assume their normal positions and the wind-wheel 80 again commence its revolution.

Having thus fully described my invention, what I claim, and desire to secure by Letters Patent, is—

1. The combination of the wind-wheel B, 85 horizontal shaft E, placed at a right angle to the face of the wind-wheel, vane F, attached to said shaft, vane G, placed at a right angle to vane F, weighted arm H, and a cord or chain for changing the position of the vanes F and 90 G, the parts being arranged substantially as and for the purpose set forth.

2. The combination of the rock-shaft E, having vanes F and G, arm J, cord j' , pipe-rod d' , and guides d'' and d''' , with the wind-wheel B, 95 as and for the purpose described.

In testimony whereof I affix my signature in presence of two witnesses.

WILLIAM S. BAUGH.
